VALVE MECHANISM FOR ROCK DRILLS

Edward F. Terry, Phillipsburg, N. J., assignor to
Ingersoll-Rand Company, Jersey City, N. J.,
a corporation of New Jersey

Application June 22, 1937, Serial No. 149,554

3 Claims. (Cl. 121—19)

This invention relates to rock drills, and more particularly to a valve mechanism for rock drills of the fluid actuated type.

One object of the invention is to assure a rapid distribution of pressure fluid to the percussive element of the rock drill.

Another object is to provide a substantially direct course for the pressure fluid flowing from supply to the percussive element.

Other objects will be in part obvious and in part pointed out hereinafter.

In the drawing accompanying this specification and in which similar reference numerals refer to similar parts:

Figures 1 and 2 are longitudinal elevations, in section, of so much of rock drills as will serve to illustrate the invention and showing the valve in the limiting positions.

Referring more particularly to the drawing, 20 20 designates a rock drill comprising a cylinder 21 having a piston chamber 22 to accommodate a reciprocating hammer piston 23. The piston controls a free exhaust port 24 and has a stem 25 slideable in a front end closure 26, for the piston chamber, to deliver blows against the working implement (not shown).

The valve mechanism, designated in its entirety by 27, is arranged in the rear end of the cylinder 21 and comprises a valve chest 28 having a recess 29 in its rearward extremity for the accommodation of rotation mechanism 30.

The rotation mechanism 30 may be conventional type consisting of a ratchet ring 31 which encircles the head 32 of a rotation bar 33 extending through the valve chest 28 and into the piston chamber 22. The head 32 carries the usual spring-pressed pawls 34 for engagement with the teeth of the ratchet ring 31, and in the rotation bar 33 are spiral flutes 35 to engage ribs 36 carried by a nut 37 threaded into the piston 23 to provide for relative rotary movement between the rotation bar and the piston.

The ratchet ring lies within the recess 29 and also extends into the front end of a back head 38 to centralize the back head with respect to the cylinder. The back head 38 forms the rearmost casing part of the rock drill. It seats directly upon the ratchet ring and may be clamped to the cylinder by any suitable means (not shown).

The back head houses a throttle valve 39 of the rotary type to control the admission of pressure fluid into the rock drill. The throttle valve has a central passage 40 which may be in constant communication with the source of pressure fluid supply and in its wall is a port 41 to register

with a supply passage or passages 42 extending through the back head, the ratchet ring 31 and the valve chest to convey pressure fluid to the valve mechanism.

As a preferred form of construction the valve chest 28 comprises an outer annular member 44 and a plug 45 extending through the outer member 44 and cooperating therewith to define an annular valve chamber 46 for the accommodation of a valve 47 whereby the distribution of pressure fluid to the piston chamber 22 is effected. The rearmost end of the valve chamber 46 preferably lies adjacent the front terminus of the supply passage 42 and communicates therewith through a supply chamber 48 encircling the valve chamber 46. Leading from a point forwardly of the supply chamber 48 and opening into the outer surface of the valve chamber is an inlet passage 49 to convey pressure fluid to the front end of the piston chamber for driving the piston 23 rearwardly.

The pressure fluid employed for actuating the piston 23 on its working stroke also passes through the supply chamber 48 and in the present instance through the rearward end of the valve chamber 46. The plug 45 is accordingly provided with an annular supply channel 50 located in the same transverse plane as the supply chamber 48 and opening into the inner surface of the valve chamber. The plug 45 is, moreover, provided with a series of inlet passages 51 which lead from the supply channel 50 to an intermediate portion of the bore 52 in the plug through which the rotation bar extends.

The passages 51 preferably open directly into the flutes 35 of the rotation bar so that pressure fluid employed for charging the rear end of the piston chamber will be conveyed thereto by the flutes 35. However, if desired, additional flow area may be provided between the passages 51 and the rear end of the piston chamber by forming an enlarged portion 53 in the part of the bore 52 extending from the passages 51 to the piston chamber.

Communication between the supply chamber 48 and the inlet passages 49 and 51 is controlled by a distributing valve 54 of the sleeve type reciprocable in the valve chamber 46. The valve has an internal flange 55 at its front end of which the outer end constitutes an actuating surface 56 which is intermittently subjected to pressure fluid for throwing the valve to its rearmost limiting position. The pressure fluid employed for this purpose is conveyed to the actuating surface 56 by a passage 57 opening into the piston chamber 55.

22 at a point immediately rearwardly of the exhaust port 24. A passage 58 in the valve chamber and the cylinder 21 vents the actuating surface 56 to the atmosphere so that compression flowing through the passage 57 during the rearward stroke of the piston will be ineffective to shift the valve.

An opposed actuating surface 59 is formed within and near the rear end of the valve. It is 10 in constant communication with the supply channel 50 and is subjected to compression flowing through the inlet passages 51 during the rearward stroke of the piston for throwing the valve 54 forwardly. The extreme rearward end of the 15 valve constitutes a holding surface 60 against which pressure fluid flowing from the supply chamber 48 to the inlet passages 51 acts for holding the valve momentarily stationary in its foremost limiting position.

20 Communication between the supply chamber 48 and the inlet passage 49 is afforded by an annular groove 61 in the periphery of the valve 54. The groove 61 is of such length that, in the rearmost limiting position of the valve, it establishes communication between the supply passage 25 48 and the inlet passage 49 and in the foremost limiting position it communicates the inlet passage 49 with an atmospheric vent 62 in the valve chamber to provide an escape for air expelled 30 from the front end of the piston chamber 22 during the working stroke of the piston so that its force will not be diminished by compression.

The operation of the device is as follows: With 35 the valve in its foremost limiting position in the valve chamber and the piston in position to begin its working stroke, as illustrated in Figure 1, pressure fluid flows from the supply chamber across the rear end of the valve into the supply channel 50, thence through the inlet passage or 40 passages 51 and the flutes 35 into the rear end of the piston chamber 22 and drives the piston 23 forwardly.

During its course through the rear end of the 45 valve chamber 46 the pressure fluid acts against the holding surface 60 and maintains the valve in the position described until the piston 23 uncovers the passage 57. Pressure fluid then flows from the rear end of the piston chamber through the passage 57 against the actuating surface 56 50 and moves the valve 54 rearwardly and holds it in that position.

When the piston 23 uncovers the exhaust port 24 the pressure fluid in the rear end of the piston chamber and that acting against the actuating 55 surface 56 is exhausted to the atmosphere. However, during the forward stroke of the piston and after it covers the free exhaust port 24 the air in the front end of the piston chamber 22 is expelled through the passage 49, the groove 61 in the valve and the atmospheric vent 62, so that 60 the piston will be unhampered by compression in the front end of the piston chamber and may, therefore, deliver a powerful blow against the working implement.

65 In the new position of the valve the groove 61 establishes communication between the supply chamber 48 and the inlet passage 49. Pressure fluid then flows from the supply chamber through the inlet passage 49 to the front end of the piston chamber and drives the piston rearwardly. During this movement of the piston, and after it 70 covers the exhaust port, the air compressed in the rear end of the piston chamber flows through the flutes 35, the passages 51 and the supply channel 50 against the actuating surface 59 and

throws the valve forwardly to its initial position. The pressure fluid employed for driving the piston rearwardly is then exhausted through the port 24, and upon shifting of the valve forwardly pressure fluid again flows from the supply chamber 48 through the inlet passages 51 and the flutes 35 to start a new cycle of operations.

In practice the present invention has been found to be highly advantageous in devices of the character to which it pertains. Owing to the 10 arrangement of the supply chamber and the inlet passages and the manner in which they communicate with each other the pressure fluid flowing from supply will follow practically a direct course to the ends of the piston chamber. This is desirable since it eliminates the power losses known to occur at deflection points. Another advantage of the present invention is that by conveying the pressure fluid through the flutes 15 35 to the rear end of the piston chamber the entrained lubricant will be deposited upon the surfaces of the flutes and those of the piston cooperating with them so that these elements will at all 20 times be adequately lubricated.

I claim:

1. In a fluid actuated rock drill, the combination of a casing having a piston chamber and a piston therein, a valve chest comprising an outer member and a plug extending through the outer member and cooperating therewith to define a 30 valve chamber, a supply chamber in the outer member opening into the rearward end of the valve chamber, an inlet passage opening into the outer surface of the valve chamber forwardly of the supply chamber and leading to the front end 35 of the piston chamber, an inlet passage in the plug opening into the rearward end of the valve chamber in the same transverse plane as the supply chamber and leading to the rear end of the piston chamber, a valve in the valve chamber to 40 control communication between the supply chamber and the inlet passages, and actuating surfaces on the valve subjected to fluid under pressure for throwing the valve.

2. In a fluid actuated rock drill, the combination of a casing having a piston chamber and a piston therein, a valve chest at the rear end of the piston chamber comprising an outer member and a plug extending through the outer member and cooperating therewith to define an annular 45 valve chamber, an annular supply chamber in the outer member encircling the valve chamber and opening into the rearward end thereof, an annular supply channel in the plug in the same transverse plane as the supply chamber and 50 opening into the rearward end of the valve chamber, inlet passages in the plug leading from the supply channel to the rear end of the piston chamber, an inlet passage opening into the outer surface of the valve chamber forwardly of the supply chamber and leading to the front end of the piston chamber, a valve in the valve chamber to 55 control communication between the supply chamber and the front inlet passage and between the supply chamber and the supply channel, an actuating surface on the valve subjected to compression for throwing the valve in one direction, and an opposed actuating surface subjected to pressure fluid valved by the piston for throwing the valve in the opposite direction.

3. In a fluid actuated rock drill, the combination of a casing having a piston chamber and a piston therein, a valve chest at one end of the piston chamber having an annular valve chamber and a bore, a rotation bar extending through 60

the bore, a supply chamber, an inlet passage leading from the outer surface of the valve chamber to the front end of the piston chamber, an inlet passage leading from the inner surface of the valve chamber to the bore, flutes in the rotation bar to convey pressure fluid from the last-mentioned inlet passage into the rear end of the

piston chamber, a valve in the valve chamber to control communication between the supply chamber and the inlet passages, and actuating surfaces on the valve subjected to fluid under pressure for throwing the valve.

5
